CARTONS

Henry W. Pupke, Teaneck, N.J., assignor to National Biscuit Company, New York, N.Y., a corporation of New Jersey

Application March 22, 1954, Serial No. 417,579

7 Claims. (Cl. 229—51)

This invention relates to improvements in reclosable cartons, and more particularly to cartons which are sealed tightly when filled and, while initially opened by breaking the seal, may be easily reclosed after a part of the contents has been removed.

Cartons of the reclosable type have become widely accepted for packaging a variety of merchandise such as cereals, crackers, cakes, tea-bags, etc., and many other articles that are commonly sold in packages containing more than one portion or unit of the commodity. After the carton has been initially opened it is customarily desirable that it be reclosed tightly until further quantities of its contents may again be wanted. It is, therefore, the main object of this invention to provide a carton possessing all of the above described general features of a reclosable carton except in a more practical, efficient and economical to manufacture embodiment than heretofore attained.

It is also one of the important objects of the invention, therefore, to provide a more practical, economical and efficient reclosable carton without resort to excessive and costly constructional elements in the carton but, rather, through the use of elements similar to those commonly employed in conventional cartons, so arranged and utilized, however, in a manner to attain the above-described objective.

It is a further object of the invention to provide a carton which is especially adapted for use in the field of fractional weight or quantity cracker packaging, particularly that of thin saltine crackers. A practice which has gained wide acceptance in recent years in the art of cracker packaging is the method of using "slug packets" each of which consists of a quantity of crackers enclosed in a heat-sealed, moisture and vapor-proof, flexible wrapper. The carton exemplified by the present invention is particularly appropriate for enclosing two or more of the above-described "slug packets." The foregoing combination of a multiple packets and the reclosable carton which will be disclosed in more detail hereinafter provides a unitary package possessing not only an appearance in keeping with good taste, but a maximum degree of protection and convenience as well.

Still another object of the present invention is to provide a carton which will protect consumer-sized units against physical damage, adulteration, or tampering with the contents therein before reaching the consumer.

An important feature of the invention is the provision of projecting tongues or tabs which form part of one of the closure flaps to serve the two-fold purpose of first, facilitating the introduction of a knife blade or similar instrument between the sealed cover panels when breaking the seal, and second, reclosing and interlocking the closure flaps after the carton has been initially opened.

It is also a feature of the invention that the carton blanks of which the carton is formed may be manufactured economically and with a high degree of efficiency. This is particularly important not only from the stand-

2

point of eliminating scrap in the formation of the blanks but also because of the high degree of mechanization which is available in carton assembling and setting-up machinery, the high operating speed of which is critically dependent upon the precision qualities of the carton blanks being supplied thereto.

The economic importance of the present invention becomes impressive when once it is realized that the over-all manufacture of cartons of this type in the United States at the present time is estimated to be over several hundreds of millions of cartons annually. One user alone is currently contemplating the production and distribution of approximately 120 million of these cartons per year, and the saving of carton material (usually paperboard) which is consumed in the production of this vast quantity of cartons is estimated to aggregate a yearly saving of approximately a quarter million dollars in material, handling and transportation costs. Actually, the saving in material is attained through a reduction in the over-all size of the mill-supplied sheets of paperboard from which the carton blanks are cut. Ordinarily, for the one pound size carton which is used for packaging four $\frac{1}{4}$ pound packets or so called "slug packs" of soda crackers, a sheet 66" x 37" is provided from which eight carton blanks are formed. From sheets of this size the well-known straight-tuck type of carton is produced. This type of carton comprises a reclosable end panel (or body panel as the case may be) extending across the entire opening at one end of the carton plus a tuck flap hinged to one edge of the panel. With the advanced design as exemplified by overlapping flaps and the reclosable feature of the carton according to the present invention it is possible to obtain eight carton blanks from a substantially smaller sheet, one which measures only 59 $\frac{1}{2}$ " x 37". This effects a distinct saving of 240.5 sq. inches of material per sheet for eight carton blanks. Thus the saving of material is not attained through reduction of the carton blank per se but, rather, it is made possible through a redistribution of surface area by the novel use of overlapping flaps which effect substantially a 10% reduction in scrap when the carton blank is cut. As a result, there is provided a low cost, precision-made carton possessing packaging advantages extendable from the producer to the distributor and to the ultimate consumer, but primarily to the latter.

In the accompanying drawings, the invention is shown merely by way of example and in preferred form, and obviously many changes and variations may be made therein which will still be comprised within its spirit. Therefore, it is to be understood that the invention is not limited to any specific form or embodiment, except insofar as such limitations are specified in the appended claims.

Referring to the drawings:

Figure 1 is a plan view of the carton blank;

Fig. 2 is a perspective view of the erected carton with the top cover flaps in open position;

Fig. 3 is a perspective view of the carton shown in Fig. 2 with the first to be folded pair of flaps in closed condition;

Fig. 4 is a perspective view of the carton shown in Fig. 3 with one of the second to be folded pair of flaps in closed condition;

Fig. 5 is a perspective view of the carton shown in Fig. 4 in completely closed and sealed condition;

Fig. 6 is a perspective view of the carton shown in Fig. 5 with the top pair of flaps in their reclosed position;

Fig. 7 is a transverse section of the top of the carton in its closed and sealed condition taken on the line 7—7 of Fig. 5; and

Fig. 8 is a transverse section, taken on the line 8—8

of Fig. 6, showing the top of the carton when in its re-closed condition.

In the construction of the carton according to the present invention, and referring now to the particular embodiment illustrated in the drawings, a blank 1 (see Fig. 1) is die cut in one piece from paperboard or other suitable material, and is provided with score lines so that the blank can be readily folded to form a completely erected carton. The blank is divided by vertical score lines S into body panels 2, 3, 4, and 5, which form the side walls of the carton. The side panel 5 is extended at one edge to provide a glue flap 6 to which the side panel 2 is attached when the blank 1 is folded into erected condition. At the bottom of the blank 1, below the horizontal score or hinge line A—A', the material is cut in alignment with the vertical score lines S, thus forming two pairs of bottom flaps 7, 8 and 9, 10. These flaps are adapted to be folded inwardly in overlapped relation and sealed to form one end of the finished carton. At the opposite end of the blank, above the horizontal score or hinge line B—B', the material is also cut in line with the vertical scores S to form two pairs of opposed flaps 11, 12 and 13, 14.

Still referring to Fig. 1, the flaps 11 and 12 are formed with tab-receiving slits or cuts 15 and 16, respectively, each of which is cut completely through the carton material and arranged parallel with but spaced a short distance inward from the hinge line B—B'. Each of the slits 15 and 16 is substantially U-shaped, being arcuately curved at both ends to form a sub-cut, the general direction of which is toward the free edge of its respective flap. The area defined by slits 15 and 16 form partially detached flap sections 17 and 18, respectively, both of which may be depressed when downward pressure is applied thereto without the deformation or displacement of other portions of the flaps. The flap 13 is formed with a locking tab 19 at the left-hand side and a locking tab 20 at the right-hand side of the free side edges of the flap. The slits 15 and 16 are formed with their openings arranged to register substantially in the erected carton with the tabs 19, 20, respectively, of the flap 13 when the flaps 11 and 12 are folded thereunder. The panel 14, on the other hand, is formed with two cut-outs or notches 21 and 22 at the left and right-hand sides, respectively, of the free edges of the flap. By thus relieving the flap 14 at both side edges, the underlying slits 15 and 16 of the flaps 11 and 12 in the erected carton remain exposed for insertion of the tabs 19 and 20.

In erecting the carton, the blank 1 is folded along each of the vertical score lines S, and the glue flap 6 is glued or otherwise sealed to the inner surface of the panel 2. The opposed pairs of bottom flaps 7, 8 and 9, 10 are then folded inward in that order and sealed in conventional manner. After the carton has been filled with its intended commodity, the flaps 11 and 12 are first folded inward (see Fig. 3) to cover the merchandise within the carton. The inner surface of flap 14 is given a spotted application of adhesive 14A (Fig. 2) along the margins of the flap in the over-all form of a U-shaped pattern 14B. Then the panel 14 is folded inward (see Fig. 4) and sealed to the underlying flaps 11 and 12. The flap 13 is also given a spotted application of adhesive 23 which also is applied in a U-shaped pattern 24 to the inner surface of the panel. The flap 13 is then folded inward, the adhesive 23 sealing it to the underlying part of the flap 14 and to the flaps 11 and 12. Referring to Figs. 3 and 4, it will be seen that the ends of the tabs 19 and 20 do not carry adhesive so that when the flap 13 is folded over as in Fig. 5, it will be relatively easy to slip the edge of a knife blade 25 (or similar instrument) underneath one of the tabs and, by running the blade between the two flaps 13 and 14, the seal may be easily broken to open the carton initially.

To reclose the carton after some of the contents have been withdrawn, it is merely necessary to fold over the

flaps 11 and 12, then the flap 14, and finally the flap 13, the tabs 19 and 20 of which are tucked or inserted by slight pressure into the slits 15 and 16, respectively, of the underlying flaps 11 and 12 (Fig. 6). The displaceable surfaces 17 and 18 which underlie the respective tabs 19 and 20 will be depressed, as best shown in Fig. 8, and the marginal hinge portion of each flap 11 and 12 will be sprung unwarily under tension, thus binding the tabs to hold the flap 13 securely in place. The free end of the flap 13 from which the tabs 19 and 20 extend laterally is of substantially the same length as the distance between the slits 15 and 16, so that the free end of the flap 13 is held snugly against the upper surface of the flap 14; and the tabs are of sufficient width to fit snugly within the slits 15 and 16. Thus, the interlocking of the flaps is such that it prevents relative movement of the flaps both in a vertical direction and in a sidewise or horizontal direction.

By this improved method of construction and enclosure, it is obvious that a carton is provided having an enclosure which is formed by two pairs of flaps which may be either firmly sealed together or interlocked in a novel manner whenever said seal is destroyed.

While one form of the invention has been shown and described, it is to be understood that either end, or any body panel, may be formed in accordance with the invention to provide the closure of the carton; and the invention is applicable to cartons which are of different shape or dimensions from those of the embodiment used as the example.

Having thus described my invention, what I claim is:

1. A reclosable carton having body and end forming panels, one of said panels comprising two pairs of opposed flaps with each flap being hingedly connected along one edge to a contiguous panel and formed to fold inward so that the flaps overlap one another when folded into closed condition and form a panel of double-walled thickness throughout substantially the entire panel area, the first to be folded pair of flaps being formed each with a slit located near to but spaced from the hinge line and extending parallel thereto, and the second to be folded pair of flaps overlying one another and the first folded pair of flaps, the underlying flap of said second pair being formed to leave said slits exposed, and the topmost flap being formed at opposite edges with projecting tabs adapted to be inserted through said slits.

2. A reclosable carton according to claim 1, wherein each flap is co-extensive with its respective panel and when initially in closed condition all four flaps are adhesively secured together along the unhinged margins of said second pair of flaps.

3. A reclosable carton according to claim 1, wherein each of said slits is intersected at its opposite extremities by a sub-cut of relatively short extension whereby a displaceable flap surface is provided to permit the insertion of the respective tab of the topmost flap without effecting any substantial deformation of the slit carrying flap.

4. A reclosable carton according to claim 1, wherein the leading edge portion of the underlying flap of said second pair is narrower than the distance between the slits in said first pair of flaps and the distance between the leading edges of the tabs on the topmost flap is greater than the distance between said slits.

5. A reclosable carton according to claim 1, wherein contiguous areas of said two pairs of flaps are initially sealed with adhesive therebetween, the undersurface of said tabs being free of said slits and from direct adhesive connection with the underlying flaps in order to facilitate the entrance of a knife blade between the flaps to break the adhesive seal.

6. A reclosable carton having four side panels and opposite end panels, one end panel comprising four flaps each hinged to one of the side panels and forming two opposed pairs of flaps adapted to be folded inwardly in overlapping relation to close the end of the carton and

form a panel of double-walled thickness throughout substantially the entire panel area, the first pair of flaps to be folded being formed each with a substantially U-shaped slit which defines a displaceable area near to but spaced from the hinge line of the flap, the first to be folded flap of the second pair being cut away at each side of its leading edge to leave the portion of each slit at the closed part of the U exposed when the flap is folded inwardly, and the outermost flap being formed with a laterally directed tab formed at each side of the leading edge portion of the flap and adapted for insertion through said slits when the carton is reclosed after once being opened, the four flaps initially being adhesively sealed along the margins of the last to be folded pair of flaps with the tabs left unsealed to permit the insertion of a knife blade for breaking the seal.

7. A reclosable end structure for paperboard cartons, comprising, in combination with the four side walls of the carton, four end closure flaps arranged in pairs connected upon folding scores with opposite side walls of the carton at one end thereof, one of said pairs furnishing two outer end flaps and the other pair furnishing two inner end flaps for arrangement beneath the said outer end flaps, said inner end flaps being provided with slit means to form a compressible portion and a locking lip in the plane of the flap and closely adjacent to its folding score at its respective side wall, said outer end flaps being

5

10

15

20

25

of an area greater than one-half the area of the carton end to thus provide for their substantially complete coverage of the inner end flaps and furnish an overlapping arrangement of their adjacent free end portions when they are folded over upon said inner end flaps, the portion of the inner one of said outer end flaps which underlies the overlapping portion of the outer one of said outer end flaps being cut away to clear said lip means, and the overlapping portion of the outer one of said outer end flaps being provided with locking tabs offstanding from its lateral edges and normally overlying but serving for engagement beneath said locking lips, the overlapping portions of said outer end flaps being adhesively secured together by a glue seam.
